UNITED STATES PATENT OFFICE.

REINHOLD KÖRSELT, OF ZITTAU, GERMANY.

PROCESS OF MAKING OXYGEN-CONTAINING SOAP POWDERS.

No Drawing.

Application filed April 9, 1924. Serial No. 705,394.

To all whom it may concern:

Be it known that I, REINHOLD KÖRSELT, citizen of the German Republic, residing at Zittau, Saxony, Germany, have invented 5 certain new and useful Improvements in Processes of Making Oxygen-Containing Soap Powders, of which the following is a specification.

This invention relates to a novel process 10 of making oxygen-containing soap-powders and similar admixtures for washing and bathing waters and consists essentially therein that by the admixture of a catalyzer into paste-like or liquid soap an air-dry 15 catalyzer mixture is produced which is mixed with the carrier of the oxygen, whereby said catalyzer may furthermore be finely pulverized and calcined carbonate of soda be added until a dry powder is obtained, and 20 a proper granulation produced for mixing the same with the carrier of the oxygen.

It is known to use oxygen for washing and bathing waters, whereby a carrier of oxygen and a catalyzer is employed. This 25 invention has for its object to distribute the discharging of the oxygen uniformly over a period of time, which may be predetermined. In the known mixtures the constituents will separate after being introduced into water; 30 by this they will at once be caused to dissolve thus being exposed to a mutual action upon each other. The discharging of the catalyzer, however, will only take place in accordance with the slow solubility of soap- 35 particles, so that an exhaustive discharge of the oxygen for washing water may take place, for instance, during ten and for bathing waters during thirty minutes. An important feature of this invention consists 40 therein, that the catalyzer is embedded in a paste of soap. The discharging of the oxygen or the action of the catalyzer upon the oxygen will take place regarding quantity and time of discharge in accordance with the 45 process of the dissolution of the soap globules. The latter may be sifted during the process of the mixture in greater or smaller sizes. According to this the duration of the 50 dissolution of the several globules of soap and catalyzer mixture and therewith the respective duration of the action or distribution of the generation of oxygen will be determined. With the present process also the stability of the product during storage 55 will be completely attained, because the

product consists of a dry mixture and the catalyzer is embedded.

As an example of the manufacture of soap powders according to this invention the following may serve. 1.5 gr. of permanganate 60 of potassium are finely ground into pulverized form in a grinding bowl and 5 gr. neutral soap, which in the meanwhile has been brought to paste-consistency by heating the same with some water in well mixed 65 with the same after cooling off.

In order to secure a quick drying, when this is desired such a quantity of calcined carbonate of soda is gradually added into the ground matter, that a gray dry powder 70 is obtained. Thereupon the catalyzer mixture is mixed—not by grinding but preferably by the aid of a mixing machine—with such a quantity of calcined carbonate of soda, that in the whole 773.5 gr. will 75 come to application.

After proper granulation, on the next day the perborate is added by intimate mixing and the packing is done at once.

This composition would correspond to a 80 skin-washing lotion for daily use or for medical purposes or for a cold rub-down, whereby the oxygen will discharge in a time which is proper for these purposes, that is in about 5 to 8 minutes. The use of warm 85 water will correspondingly abbreviate the time of the discharge of the oxygen.

If the soap according to this invention shall be applied for the purpose of baths, whereby in most cases warm water is applied, about one third of the above-mentioned quantity of permanganate of potassium would appear sufficient. For baths of a duration of 15 to 20 minutes the dose for skin-washing purposes would also suffice, 95 if the bathing person will add the intended quantity during bathing in certain intervals.

Having thus described my invention, I claim as new and desire to secure by Letters 100 Patent of the United States:

1. The process of making oxygen-containing soap powders and similar admixtures for washing and bathing waters, which consists in mixing potassium permanganate 105 with paste-like soap, and mixing the same with an oxidizing agent.

2. Process of making oxygen-containing soap powders and similar admixtures for washing and bathing waters, which con- 110

sists in well mixing finely pulverized potassium permanganate with paste-like soap, adding calcined carbonate of soda to the mixture until a dry powder and a proper granulation is obtained and mixing said powder with an oxidizing agent.

3. The process of making oxygen containing soap powders and similar admixtures

for washing and bathing, which consists in well mixing finely pulverized potassium permanganate with paste-like neutral soap, adding calcined sodium carbonate to the mixture until a dry powder and a proper granulation results, and mixing said powder with a perborate.

REINHOLD KÖRSELT.
